UNITED STATES PATENT OFFICE.

WILLIAM K. LIGGETT, OF COLUMBUS, OHIO, ASSIGNOR TO THE JEFFREY MANUFACTURING COMPANY, A CORPORATION OF OHIO.

PULVERIZER.

1,085,692.

Specification of Letters Patent.

Patented Feb. 3, 1914.

Application filed December 15, 1908. Serial No. 467,702.

To all whom it may concern:

Be it known that I, WILLIAM K. LIGGETT, a citizen of the United States, residing at Columbus, in the county of Franklin and

5 State of Ohio, have invented certain new and useful Improvements in Pulverizers, of which the following is a specification, reference being had therein to the accompanying drawing.

10 This invention relates to pulverizers and has as its object the provision of improved feeding mechanism for delivering the material to the pulverizing chamber, improved construction and mounting of the breaker plates and the screening bars, improved hammer mechanism, and improved arrangement of the frame parts generally of the machine.

15 Of the drawings Figure 1 is a view in side elevation of the machine as a whole. Fig. 2 is a vertical cross-section, taken along the line 2—2 of Fig. 1. Fig. 3 is a plan view of the machine with the feed-hopper removed. Fig. 4 is an enlarged vertical longitudinal section through one of the bearings.

20 Fig. 5 is an end view, partly in vertical cross-section, of the parts shown in Fig. 4. Figs. 6 and 7 are fragmentary views in longitudinal section illustrating the manner in which the hammers are mounted. Figs. 8 and 9 show one of the hammer-supporting disks upon a scale reduced in comparison with that of Figs. 6 and 7. Figs. 35 10 and 11 show enlarged detail views of one of the hammers. Figs. 12, 13 and 14 illustrate the manner in which the hammer block is adjusted to different positions as it is worn away. Figs. 15, 16 and 17 are views of the side frame for supporting the

40 screen bars. Figs. 18 and 19 show one of the screen bar sections. Fig. 20 is a fragmentary perspective view showing the manner in which the screen bar sections and the side supporting frames are assembled.

45 Figs. 21 and 22 show the plates which are secured to the sides of the casing above the bearings. Fig. 23 shows the hardened linings in the interior of the end plates of the casing.

50 The frame of the pulverizer consists of the side plates 1 and 2 and the end pieces 3, 3 to which the side plates are bolted. The end frame pieces 3, 3 are each provided with central apertures 4 to receive the main

55 shaft and with vertical slots 5 extending up-

wardly from these central apertures, by means of which the shaft can be lowered into position.

The bearings for the shaft each have the upper and lower outer shells 6 and 7 which are bolted together about the shaft. The lower of these shells is provided with a semi-circular flange 8 near its inner end by means of which it is bolted to the semi-circular bosses 9 cast on the end plate 3. Both the upper and lower shells are provided with a flange 10 extending radially outward which is machined to have a smooth surface and which comes into close contact with the flange 11 upon the end piece upon the lower side of the bearing, and on the upper side of the bearing with the cover plate 12 which is bolted to the upper semi-circular boss 13 upon the end frame piece. The cover plate 14 is bolted in place over the vertical slots 75 5 and in this manner the end of the machine is completely closed so that no dust can find its way out from the pulverizer chamber to the exterior of the machine.

Within the shells 6 and 7 is mounted the cylindrical bearing 15, in which is secured the bearing bushing 16. This bearing is provided with the annular flange 17 curved outward in cross sectional contour which engages and bears upon the inwardly projecting cylindrical flange 18 of the bearing shells 6 and 7 and is held in place against longitudinal and rotative displacement with respect thereto by means of the dowel pins 19, fitting within the recess 20 in the flange 18.

The bushing is held against longitudinal and rotative displacement with respect to the bearing 15 by means of the dowel pins 21 having enlarged inner ends 22 and having their outer ends upset to form the rivet heads 23. The ring oilers 24 operate in the usual manner to lubricate the shaft bearing. The chamber 25 is filled with lubricant through the openings 26 which are normally closed by screw plugs. Each of the bearing shells 6, 7 is provided with double flanged ends 27 and the annular recess 28 between the flanges is adapted to receive the felt or other packing by means of which dust is prevented from entering the bearing and the oil is prevented from leaking out around the shaft.

The construction of the bearings as a whole and the adjacent parts of the casing 110

of the machine is such that dust is prevented from entering the bearing or from finding its way out around the bearing to the exterior of the machine, a slight ball-and-socket movement and also end play of the shaft is permitted at each side of the machine, protection is afforded to all of the bearing parts, and the thorough lubrication of the bearing surfaces is effected without permitting the oil to escape from the bearing chamber.

The shaft 34 has keyed upon it at one end the drive pulley 29 and at the other end the fly-wheel 30. These parts are also fixed against longitudinal displacement with respect to the shaft, thus also securing the shaft from longitudinal displacement with respect to the machine as a whole.

Upon the shaft and immediately within the end frame pieces 3, 3 of the casing of the machine are keyed the end plates 31, 31. These plates are provided with a circular series of openings 32 therethrough and parallel to the axis of the shaft. A series of disk plates 33 are keyed to the shaft between the end plates 31, and each of these disks is perforated near its periphery at points 35, 35 corresponding with the perforations 32 in the end plates 31. The disks 33 and end plates 31 are assembled upon the shaft with these perforations in alignment from end to end of the machine, and by means of these perforations the rods 36 are mounted in series about the shaft 34 as a center. The alternate rods of these series are preferably of a larger diameter than the remaining rods and upon these larger rods are mounted the hammer arms 37.

In pulverizers, as heretofore constructed, the hammers, which are usually rectangular parallelepipeds, are pivotally mounted upon the rods 36 between the outer ends of adjacent spider arms. The outer ends of the hammers wear away rapidly under the action of the rock and stone as the latter is ground against the concave or grate bars, and they must therefore be frequently replaced. It is one of the objects of this invention to do away with the necessity for frequently replacing these hammers. Accordingly the hammer arms 37, which are pivoted at their inner ends to the rods 36 are enlarged somewhat at their outer ends. Each arm is bifurcated at its outer end to form a pocket 38, generally rectangular in shape, in which is fastened the hammer block 39. This pocket 38 is open in front and on the outer face of the hammer and has the rear wall 40, the side walls 41, 42, and the bottom 43.

The hammer pieces 39 are blocks with four rectangular edge faces and two square side faces. They are mounted upon the pins 44 which pass centrally through the hammer blocks and are supported in the side walls

41 and 42. That part of the pin which engages with the wall 41 is of a smaller diameter than the remainder of the pin which engages the hammer block and the other side wall 42. The pins can thus be readily inserted in place, the shoulder 45 acting as a stop to prevent longitudinal displacement of the pin in one direction. As is shown in Fig. 7, the pins of adjacent hammer arms are placed with their large ends toward each other, which arrangement acts to prevent longitudinal displacement of the pins in the other direction. If the hammer arms are spaced across the machine in a manner to leave a gap between adjacent arms, as is often desirable, an intermediate arm 46 is mounted, as shown in Fig. 6, to act as an abutment for the pins upon each side of it and prevent their accidental removal from place.

Fig. 12 shows the hammer block in its first position, the dotted line indicating its shape when worn. Since the hammer block is centrally mounted and solidly engages the rear wall 40 of the hammer arm, by removing the pin, giving the block a quarter turn and again replacing the pin, a second edge of the block is available as a working face. This operation can be again repeated, three of the edges of the block being successively presented to the concaves and worn away before it becomes necessary to insert a new block.

The side walls 41 and 42 of the arms are not extended outwardly as far as the hammer block and are not subject to the same degree of wear and abrasion. The life of the hammer arms is considerably lengthened by employing the construction herein described and it is seldom necessary to replace the arms or the pins which hold the blocks in place.

The alternate spaces between the disks 33 are regulated and fixed in amount by the filler blocks 47 on the rods 36. Rods 49 of smaller diameter than that of rods 36 are mounted in the rows of perforations or apertures positioned alternately between the longitudinal rows of apertures which receive the rods 36. These smaller rods serve as rests for the hammers when the machine is idle in the manner illustrated by the dotted line representations of the hammers in Fig. 2. Filler blocks can also be mounted on rods 49 between each two of the disks 33 to assist in spacing the disks and add greater rigidity to the hammer supporting structure. These alternate rods of smaller diameter prevent the hammers in adjacent rows from interfering with each other and becoming entangled, and particularly prevent the outer end of one hammer from becoming caught by the inner end of the hammer in the next adjacent row.

Between the end frames 3, 3 of the ma-

chine are bolted the curved plates 50, 51, forming part of the upper casing of the machine. To each of these plates is secured the linings 52 of special hardened steel 5 which serve as breaker plates for the material. There is also bolted to the end frames 3, 3, the inclined plate 53 and top breaker plate 54.

The material is fed to the opening 55 by 10 means of the plate feeder 56, reciprocated by means of gearing indicated as a whole by 57, which automatically and in a constant stream feeds the material from the hopper 58 to the pulverizing chamber. It will be 15 observed that the material as it falls through the opening 55 first engages the inclined plate 53 from which it falls directly into the path of the moving hammers as they traverse the upper approximately horizontal 20 part of their circular path of rotation. In this way the material is first acted upon by the hammers while it is moving freely through the pulverizing chamber and out of contact with any of the inclosing surfaces of 25 that chamber. It will, of course, be understood that the shaft is rotating when the machine is in operation at a velocity so great that the material has no opportunity to fall between the hammers but that all of 30 the material is thrown outwardly with great force first against the breaker plates 54 and 52 and afterward against the other grinding surfaces of the pulverizer. These grinding surfaces consist of the adjustable breaker 35 plate 59 and the screen bar concaves 60 and 61. The adjustable breaker plate 59 can be moved horizontally toward and away from the hammers by means of the adjusting screws 62. This mechanism has been de- 40 scribed and illustrated and claimed in my application, Serial No. 357,072, filed February 12, 1907.

The screen bar concave 60 consists of the 45 end supporting frames 63, 63, and the screen bars 64. The end frames 63 are each pivotally secured to the end frame pieces 3, 3 of the machine as a whole at their upper ends, as shown at 65, and at their lower ends 50 rest upon the wedge-shaped supports 66. By adjusting these supports 66 toward and away from the transverse central plane of the machine, the lower end of the concave 60 is lifted toward or lowered away from the hammers. The end frames 63 are keyed 55 upon the shaft 65 to which they are secured to prevent longitudinal displacement and near their lower ends they are likewise joined by means of the tie-rod 67. These end frames 63 are provided with curved 60 grooves 68 which are adapted to receive the ends of the screen bar sections. The screen bars 64 are riveted together in sections, as shown in Figs. 18 and 19, filler blocks 69 being used at the ends of the screen bars and 65 at one or more points intermediate the ends

to bind the bars into one rigid structure. The screen bar section shown in Figs. 18 and 19 is offset at the ends to provide shoulders 70 adapted to engage the shoulders 71 at the lower end of the grooves 68. It is evident that because of this manner of assembling the parts, they can be readily disassembled by simply loosening the screws which secure the end frames 63 to the pivot rod 65 and tie-rods 67 and moving these end frames away from each other. At the same time when the parts are assembled the screen bars are held firmly in position. By the manner in which the screen bars are rigidly secured together with rivets and 75 filler blocks, both at their ends and at intermediate points, it is possible to continue operating the machine after one of the bars has become broken, the adjacent parts holding the broken ends temporarily in position. 80 The screen bar concave 61 is made up of parts similar to the parts of concave 60 and it is likewise pivoted at its upper end to the end frame pieces 3, 3 of the machine by means of the cross-rod 72. To each end of 85 the tie-rod 73, by which the lower parts of the two screen bar supporting frames 74 are held at a fixed distance from each other, is pivotally secured a link 75. The other end of each of these links 75 is pivoted to 90 a second link 76 which is rigidly secured to the cross-rock shaft 77, the latter being pivotally mounted in bearings in the ends of the machine. This shaft can be rocked by means of the weighted lever 78. When the lever is 95 in the horizontal position, as shown in full lines in Fig. 2, the concave 61 is in operative relation with the other parts of the machine. When the lever 78 is thrown to its upper position the lower end of the concave 61 is 100 lowered and the pulverizing chamber can be cleaned or freed from metallic pieces or other undesirable objects which may have accidentally found their way into the pulverizing chamber.

The end frame pieces 3, 3 of the machine are interiorly faced with the hardened steel lining plates 79 which protect the end plates from the wear to which they are subjected from contact with flying particles of material. These plates do not extend inwardly toward the center of the machine, but considered together constitute a ring, the inner diameter of which is approximately the diameter of the disks 33 and the outer diameter of which is the diameter of the 115 pulverizing chamber. This ring is, however, provided with an upward extension to protect those parts of the end pieces 3, 3 which lie adjacent to opening 55 and the top 120 breaker plate 54.

What I claim is:

1. In a pulverizer, the combination of a rotatable radial arm, medially recessed at its outer end to form a pocket open in front 130

and at the outer edge of the arm, the pocket having side walls and a rear wall, a pin secured to and extending perpendicularly between the side walls of the said pocket, and 5 a hammer block mounted on said pin between the side walls and abutting solidly against the rear wall.

2. The combination in a pulverizer, of a rotatable radial arm having formed thereon 10 a plane face approximately perpendicular to the circles of rotation of the arm, a prismatic wearing block having a plurality of plane side faces, and means for securing the block with its prismatic axis parallel to the 15 axis of rotation of the arm and in front of the plane face of the arm and with any one of its said plane faces flatly in contact with the plane face of the arm.

3. The combination in a pulverizer, of a 20 rotatable frame, a plurality of radial arms pivoted thereto in axial rows, each of said arms being bifurcated at its outer end in planes longitudinal of the machine, pins mounted in and between each pair of the 25 said bifurcations, hammer blocks mounted on the pins, means for preventing the axial displacement of each pin in one direction with respect to its arm, and means for preventing the axial displacement of the adjacent 30 pin of the same row in the other direction with respect to its arm, all of the pins in each row axially alining with each other.

4. The combination in a pulverizer, of a rotatable frame, a plurality of radial arms 35 pivoted thereto in axial rows, each of said arms being bifurcated at its outer end in planes longitudinal of the machine, pins mounted in and between each pair of the said bifurcations, hammer blocks mounted 40 on the pins, means for preventing axial displacement of each pin in one direction with respect to its arm, means for preventing the axial displacement of the next adjacent pin of the same row in the other direction with

respect to its arm, all of the pins in each 45 row axially alining with one another, and abutment pieces mounted to occupy the space between the ends of adjacent pins in each row.

5. The combination in a pulverizer, of a 50 rotatable frame, a plurality of radial arms pivoted thereto in axial rows, each of said arms being bifurcated at its outer end in planes longitudinal of the machine, pins mounted in and between each pair of the 55 said bifurcations, and hammer blocks mounted on the pins, mating shoulders being formed on each pin and one of the bifurcations supporting it to prevent axial displacement in one direction, the pins of each 60 adjacent pair being thereby prevented from displacement in directions away from each other, the two pins being in axial alinement with each other.

6. The combination in a pulverizer, of a 65 rotatable frame, a plurality of radial arms pivoted thereto in axial rows, each of said rows being bifurcated at its outer end in planes longitudinal of the machine, pins mounted in and between each pair of the 70 said bifurcations, and hammer blocks mounted on the pins, mating shoulders being formed on each pin and one of the bifurcations supporting it to prevent axial displacement in one direction, the pins of each 75 adjacent pair being thereby prevented from displacement in directions away from each other, the two pins being an axial alinement with each other, and an abutment member mounted to occupy the space between the 80 ends of the two pins.

In testimony whereof I affix my signature, in presence of two witnesses.

WILLIAM K. LIGGETT.
